[57] CLAIM

The ornamental design for a lady's shoe or similar article, substantially as shown and described.

DESCRIPTION

FIG. 1 is a front perspective view of a lady's shoe or similar article showing my new design, the broken line depiction of a T-strap being illustrative of environment only;

FIG. 2 is a top plan view thereof; and

FIG. 3 is a rear elevational view thereof.
